UNITED STATES PATENT OFFICE.

EUGENE L. MAUPAI, OF NEW YORK, N. Y.

PROCESS OF DYEING RAW SILK.

1,352,014.

Specification of Letters Patent.

Patented Sept. 7, 1920.

No Drawing.

Application filed June 14, 1920. Serial No. 388,811.

To all whom it may concern:

Be it known that I, EUGENE L. MAUPAI, a citizen of the United States of America, residing at New York city, county and State 5 of New York, have invented certain new and useful Improvements in Processes of Dyeing Raw Silk, of which the following is a full, clear, and exact description.

This invention relates to an improvement 10 in the process of treating and dyeing raw silk, the object being to provide a process whereby certain elements, such as metallic salts, are used to harden the cereaceous matter or fatty substances contained in grege silk, 15 so as to render the same in condition whereby the silk will be resistant to the action of strong alkali or acid solutions, thus putting the silk in such condition as to readily allow the same to be dyed with vat colors, such as 20 indanthrine, algol, helindone or the like. So far as I am aware, it has heretofore been impossible to dye grege silk with such colors, because of the high percentage of alkali 25 present in the dye.

In carrying out my invention, I proceed as follows:

I first saturate the silk with a metallic salt, diluted in water, such for instance as chrome chlorid, iron liquor or alum, thus 30 producing an insulation or hardening of the fatty matters or cereaceous substances contained in and around the silk threads.

Thereupon the silk is washed and then dyed in the usual manner with vat colors, whereupon the silk is woven into fabric. The fabric is then washed in a soap or alkali solution, such as is used in degumming silk. 35

What I claim and desire to secure by Letters Patent is:—

1. The process of treating and dyeing 40 grege silk, which consists in first hardening the silk threads with a metallic salt, thereupon washing the silk, and then dyeing the same with vat colors.

2. The process of treating and dyeing 45 grege silk, which consists in first hardening the silk threads with a metallic salt, thereupon washing the silk, then dyeing the same with vat colors, weaving the silk into a fabric and thereupon degumming the silk 50 fabric.

3. The process of treating and dyeing raw silk, which consists in saturating the silk with a metallic salt to produce a hardening of the cereaceous substances contained in the 55 silk, then washing the silk, then dyeing the silk with vat colors, and thereupon degumming the dyed silk.

Signed at New York city, N. Y., this 11th day of June, 1920.

EUGENE L. MAUPAI.

Witnesses:

MAURICE BLOCK,
EDWARD A. JARVIS.
